UNITED STATES PATENT OFFICE.

ALFRED A. ZIEGLER, OF BOSTON, MASSACHUSETTS, ASSIGNOR TO UNITED ELECTRIC APPARATUS CO., OF BOSTON, MASSACHUSETTS, A CORPORATION OF MASSACHUSETTS.

CONTACT-PIN FOR CIRCUIT-CLOSING MEMBERS.

1,197,168.

Specification of Letters Patent. Patented Sept. 5, 1916.

Original application filed February 18, 1910, Serial No. 544,530. Divided and this application filed April 25, 1912. Serial No. 698,120.

To all whom it may concern:

Be it known that I, ALFRED A. ZIEGLER, a citizen of the United States, residing at Boston, in the county of Suffolk and State 5 of Massachusetts, have invented an Improvement in Contact-Pins for Circuit-Closing Members, of which the following is a specification.

This invention relates to circuit-closing devices and particularly to the contact-pins, and has for its object the formation of a contact-pin of a single piece of wire, such as platinum, comprising a body and a head with a flat end, said head being larger in 15 diameter than the body, and the pin being frictionally secured in a hole in the circuit-closing member with its head projecting therefrom and engaging the surface of the member.

20 The present invention involves a contact-pin which is formed and secured to the member at one and the same operation. Such a contact-pin is not liable to cause trouble as it cannot work loose and is well suited for 25 electric devices which are subjected to rough usage.

Figure 1 is a side elevation of a circuit-closing device, the members of which have contact-pins embodying this invention. Fig. 30 2 is a transverse section of one of the circuit-closing members having a short piece 35 of wire projecting through a hole therein and illustrating the first step of forming and securing the contact-pins to the member. Fig. 3 is a similar view, the wire having been subjected to 40 endwise pressure by dies to form the contact-pin and frictionally secure it to the member. Fig. 4 is a vertical section of another circuit-closing member having a 45 hole in the end of its shank and a short piece of wire inserted in said hole, thus illustrating the first step of forming and securing the contact-pin. Fig. 5 is a similar view, the wire having been subjected to endwise pressure by dies to form the contact-pin and secure it to the circuit-closing member.

50 Referring to Fig. 1 of the drawings, which illustrates one form of an electrical device to which my improved form of contact-pin is applicable, *a* represents the base-plate, *b* a resilient circuit-closing member, *d'* a bracket arranged on the base-plate through which a screw *d'* extends, which is located

above the member *b*, and *f* a post set in the 55 base-plate beneath the member *b*, said member being movable between the screw and the post. Contact-pins embodying my invention are arranged in the member *b*, and in the screw, and may be arranged in the 60 post.

Referring to Figs. 2 and 3 the member *b* is shown as having a hole through it for the contact-pin. In Fig. 2 *b'* represents a short piece of metal, as wire, for instance, which is 65 extended through the hole in the member *b*, its ends projecting from both sides of the member. Said single piece of metal *b'* is then subjected to endwise pressure by dies, which, by a swaging or equivalent action 70 slightly enlarge the portion of the wire which is in the hole to cause it to snugly fit said hole and substantially enlarge the projecting end-portions of the wire to form cylindrical heads at each end of the wire, 75 outside of the hole, each head having a flat end. The contact-pin thus formed frictionally engages the wall of the hole in the member and the heads abut against the upper and under sides of said member, and as a 80 result it is very securely attached to the member *b*. Forming and securing the contact-pin thus takes place at one and the same operation.

Referring to Figs. 4 and 5 a circuit-closing member shown as a screw *d'* is shown, having a hole in the end of its shank for the contact-pin, and said pin is formed and secured therein in substantially the same manner as heretofore described, that is to say, a 85 short piece of wire *d* is inserted in the hole and subjected to severe endwise pressure by a die, which slightly expands the portion contained in the hole, in order that it may 90 frictionally engage the wall of the hole and also forms a circular head with a flat end at the end of the screw, said head being 95 larger in diameter than the portion contained in the hole. This contact-pin, like the aforesaid contact-pin, is formed and secured at 100 one and the same operation.

From the foregoing it is obvious that the contact-pin may be formed and secured to any other form of circuit-closing member than that here shown.

105 I claim:

A circuit closing member having a hole closed at the bottom and a contact pin there-

for composed of an integral metallic section including an elongated body and a circular head larger than the body and having a free flat face concentric with the surface of the body, the body of the pin completely filling and being frictionally held within the hole within the member, the head of the pin engaging the surface of the member adjacent the hole and presenting an area of greater diameter than, and concentric with the body whereby the continual blows on the head in-

cident to contact pressure will tend to spread the body within the hole and thereby maintain its frictional engagement therewith.

In testimony whereof, I have signed my ¹⁵ name to this specification in the presence of two subscribing witnesses.

ALFRED A. ZIEGLER.
